CLAIM

The ornamental design for a display screen or portion thereof with a graphical user interface for running an assessment showing the new design.

DESCRIPTION

The FIGURE is a display screen or portion thereof with a graphical user interface for running an assessment showing the new design.

The outer perimeter shown as long-dash broken line in the drawing illustrates a display screen or portion thereof and forms no part of the claimed design. The remaining broken lines in the drawing illustrate portions of the graphical user interface that form no part of the claimed design.

Assignee: VoxNeuro Inc.	Examiner: Cary M. Robinson
Abstract	
A display screen or portion thereof with a graphical user interface for running an assessment showing the new design. The outer perimeter shown as long-dash broken line in the drawing illustrates a display screen or portion thereof and forms no part of the claimed design. The remaining broken lines in the drawing illustrate portions of the graphical user interface that form no part of the claimed design.	
Claims	
1. An ornamental design for a display screen or portion thereof with a graphical user interface for running an assessment showing the new design, characterized by the features set forth in the claims.	
Description	
The FIGURE is a display screen or portion thereof with a graphical user interface for running an assessment showing the new design. The outer perimeter shown as long-dash broken line in the drawing illustrates a display screen or portion thereof and forms no part of the claimed design. The remaining broken lines in the drawing illustrate portions of the graphical user interface that form no part of the claimed design.	
Drawings	
1 drawing sheet(s) showing the ornamental design for a display screen or portion thereof with a graphical user interface for running an assessment showing the new design.
